UNITED STATES PATENT OFFICE

WILLIAM E. BELL, OF HONOLULU, TERRITORY OF HAWAII, ASSIGNOR OF ONE-HALF TO
L. L. McCANDLESS, OF HONOLULU, HAWAII

AUTOMATIC VALVE

Application filed October 12, 1931. Serial No. 568,472.

The invention relates to a valve construction and more especially to automatically operated valve mechanisms for flush tanks.

The primary object of the invention is the provision of mechanism of this character wherein both the inlet and outlet valves of the flush tank will be automatically controlled and in the construction eliminates the usual fault of the various types of standard valves operative within the water in the flush tank as these corrode, the mechanism performing the dual function to control the intake and also the outlet to and from the tank.

Another object of the invention is the provision of mechanism of this character, wherein the construction thereof is novel in form and the controlling element being disposed outside of the flush tank and in the operation thereof automatically regulates the intake of water to the tank on the operation of the outlet valve for discharge of water from the tank.

A further object of the invention is the provision of mechanism of this character which is comparatively simple in construction, thoroughly reliable and efficient in its purpose, readily and easily accessible and susceptible of adjustment for the automatic working thereof and also inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claim hereunto appended.

In the accompanying drawings:—

Figure 1 is a top plan view of the flush tank showing the intake and outlet with the mechanism constructed in accordance with the invention installed.

Figure 2 is a front elevation.

Figure 3 is an enlarged fragmentary elevation of the mechanism, a part thereof being in section.

Figure 4 is a fragmentary detail plan view.

Similar reference characters indicate corresponding parts throughout the several views in the drawings.

Referring to the drawings in detail, A designates a flush tank of standard type or 55 design having associated therewith the water inlet pipe 10 and water outlet pipe 11, the latter being extended to a toilet bowl (not shown) for the flushing thereof in the usual well known manner.

The outlet pipe 11 leading from the tank A is normally closed by a lift valve 12 and is operated from a rotatable hand piece 13, the same being located outside of the front of the tank A and has journaled in its front 65 wall the turning shaft 14 of which being disposed transversely of the tank and suitably journaled in both the front and back walls thereof. This shaft 14 carries a cam projection 15 which operates upon a crank 16, the latter being connected through the medium of the link 17 with the lift valve 12 so that upon rotation of the hand piece 13 the valve 12 will be lifted from its seat 70 for the opening of the outlet pipe 11 to 75 permit the water within the tank to flush a toilet bowl.

The intake pipe 10 which opens into the tank A for supplying water thereto has arranged in its vertical stretch exteriorly of 80 said tank a valve casing 18, the plug 19 of which is formed with a stud or lug 20 received in an elongated slot 21 in a turning lever 22, the lug or stud being detachably engaged with the lever through the 85 medium of the cotter pin 22' and this lever is designed to turn the plug which is the valve proper in the casing 18 for the opening and closing of said intake pipe 10 in a manner presently described. Suitably sup- 90

ported adjacent to the intake pipe 10 close to the valve casing 18 is a cylinder 23 in which works a piston 24 on a stem or rod 25 slideable through a collar 26 adjustably mounted in the upper end 27 or head for 95 the cylinder 23 and this stem or rod has pivoted thereto as at 28 the lever 22 so that on upward movement of the stem or rod 25 the plug valve 19 will be rotated through 100 the instrumentality of the lever 22 for the

opening of the valve in the intake pipe 10 to permit the filling of the tank A and upon downward movement of said stem or rod 25 the plug valve 19 will be closed.

- 5 Mounted upon the support for the tank A next to its rear wall is a rocker 28, the end 29 of which being engaged by a nut 30 adjustably fitted on the upper free end of the stem or rod 25 while the opposite end 31 plays against the cam 32 on the shaft 14 of the hand piece 13 and this cam 32 being located over the rocker 28 and outside of the tank A. Thus it will be seen that when the hand piece 13 is swung in 10 one direction the cam 32 will impart movement to the rocker 28 whereby the stem or rod 25 will be lifted and in this manner the plug valve 19 opened in the casing 18 in the intake pipe 10 for the filling of the flush 15 tank A as will be obvious.

Coiled about the stem or rod 25 within the cylinder 23 is a coiled expansion spring 33, one end bearing against the piston 24 while its opposite end is seated against an 20 annular flange 34 on the inner end of the collar 26, which latter is adjustable in the end or head 27 of the cylinder 23 to vary the tension of the spring 33 which is active upon the piston 24 to lower the same within 25 the cylinder 23 upon the lifting or upward movement of said stem or rod 25 and this spring functions to automatically close the plug valve 19 in the valve casing 18.

The end or head 27 of the cylinder 23 is 30 formed with suitable apertures 35 to permit the escapement of air from the cylinder 23 upon upward movement of the piston 24 therein. The piston 24 is provided with suitable packings 36 so as to prevent the 35 possibility of air passing from the upper side of the cylinder 23 to the lower side thereof relative to the piston 24 therein.

It will be apparent that when the hand piece 13 is operated to lift the valve 12 the 40 plug valve 19 will be simultaneously operated for the opening of the intake to the tank A and the quantity of water admitted to the tank A from the intake pipe 10 is determined by the time it takes the 45 piston 24 to finish its downward movement in the cylinder 23 under the action of the spring 33 upon this piston.

It will also be observed that the mechanism for controlling the intake valve 19 is 50 located outside of the tank so that corrosion of such mechanism is eliminated as the same will not be subjected to water which would be the case if located within the tank A.

Fitted in the bottom of the cylinder 23 55 is an adjusting screw 37 which controls a plurality of escapement ports 38 in the bottom of said cylinder whereby the speed of downward movement of the piston 24 in its action can be determined as the escapement of air from between said piston and

the bottom of the cylinder 23 can be regulated by this screw 37 which controls the size of the escapement ports 38 under adjustment thereof.

What is claimed is:—

The combination with a flush tank having a swinging operating lever provided with a cam and a valved water inlet, of a turn lever connected with the valve of the water inlet with sliding connection therebetween, a cylinder having a removable head and a vented end opposite thereto, a vent control screw operating with respect to said vent, a piston within the cylinder and having a stem passed through its removable head, a follower plate adjustably engaged in the removable head, a coiled tensioning spring between the plate and piston, a pivot connection between the lever and said stem, a rocker operable by the cam of said first named lever and straddling the same, and a half-spherical nut adjustably engaging the stem and forming a fulcrum for the straddling lever.

In testimony whereof I affix my signature. *WILLIAM E. BELL.*
